CLAIM

The ornamental design for a panel bed, as shown and described.

DESCRIPTION

FIG. 1 is a perspective view of a panel bed according to an embodiment of the invention.

FIG. 2 is a front view of a headboard of a panel bed according to an embodiment of the invention.

FIG. 3 is a front view of a footboard of a panel bed according to an embodiment of the invention.

FIG. 4 is an overhead view of a panel bed according to an embodiment of the invention; and,

FIG. 5 is a side view of a panel bed according to an embodiment of the invention, the view from the opposite side being a mirror-image thereto.

The headboard and footboard are shown separately for convenience of illustration.
